MACHINE FOR OPERATING ON SHOE PARTS

Axel A. Lawson, Beverly, Mass., assignor to
United Shoe Machinery Corporation, Paterson,
N. J., a corporation of New Jersey

Application April 1, 1937, Serial No. 134,367

41 Claims. (Cl. 12—51)

This invention relates to machines for operating on shoe parts and is illustrated herein with particular reference to molding or conforming upper materials such, for example, as quarter linings.

Quarter linings for shoes are usually made from relatively thin, pliable leather and, while some of them are made in two pieces with a central or "back" seam therein which makes it possible by proper cutting of the parts to produce a bulge or "pocket" in the quarter lining for fitting over the heel end portion of a last, many quarter linings are cut from a single piece of material which will not fit smoothly around the curvature at the heel portion of a last.

Objects of the present invention are to provide an improved machine for shaping shoe parts to fit the curvature of a last and to provide an improved method of shaping such parts.

In accordance with one feature of the invention means is provided for holding a work piece such as a quarter lining with a portion thereof unsupported and for clamping the work piece at and completely around the periphery of the unsupported portion. The unsupported portion is then molded and stretched by additional means to form a last receiving bulge, this additional means being adapted to stretch the unsupported portion of the work piece substantially uniformly throughout its entire area. As herein illustrated, the supporting means comprises a block with an opening of predetermined size and shape therein and the clamping means is constructed and arranged to clamp a substantial width of the work piece surrounding said opening in a flat position and with substantially equal pressure throughout, said clamping means being arranged to adjust itself automatically for operating on work pieces of different thicknesses. Moreover, the pressure of said clamping means is sufficient to insure against the work piece slipping and thereby causing its original shape or periphery to become deformed. The uniform stretching of the quarter lining during the molding of the bulge therein is attained, as herein illustrated, by reducing friction between the work piece and the molding means, which is in the form of a plunger, so that the portion of the work piece engaged by said plunger will be stretched as much as portions that are bridged between the plunger and the periphery of the opening in the supporting block. The plunger is shaped in plan view to correspond to the shape of the opening in the supporting block and is convex on its work engaging surface to produce the desired bulge.

In accordance with another feature of the invention the plunger is arranged to be moved positively a predetermined distance, in shaping a quarter lining, by power operated mechanism and means is provided independent of the power operated mechanism for adjusting the position of the plunger relatively thereto and in accordance with the size and thickness of the work.

Still another feature of the invention resides in improved means for determining the position of the work piece on the supporting block, said means also acting as an ejector for automatically removing the work from the machine after it has been operated upon. As herein illustrated, the combined gaging means and ejector is adjustable relatively to the supporting block and the arrangement is such that this adjustment may be accomplished without diminishing its effectiveness as an ejector.

In its method aspect the invention provides an improved procedure for treating quarter linings for shoes which comprises clamping an annular portion of a quarter lining in a substantially flat position with a central or intramarginal portion thereof unsupported, and forcing the unsupported portion out of said flat position to mold a last receiving bulge therein, the molding action operating also to stretch the entire unsupported portion beyond the limit of its elastic recovery so as to render the bulge permanent.

With the above and other objects and features in view, including also improved means for facilitating the ejection of the work from the machine, and means for preventing injury to the operator in handling the work, the invention will now be described in connection with the accompanying drawings and will thereafter be pointed out in the claims.

In the drawings,

Fig. 1 is a side elevation of the machine embodying the present invention with parts broken away and in section;

Fig. 2 is a detail view of a work supporting and receiving device with which the machine is provided;

Fig. 3 is a plan view of the machine with the top cover removed;

Fig. 4 is a plan view of the operating instrumentalities at the front of the machine with upper portions omitted;

Fig. 5 is an enlarged perspective view showing a cross section of an edge portion of the clamping member or holdown and illustrating the manner in which a rubber facing member is attached thereto;

55

Fig. 6 is an enlarged longitudinal section through the center of the front portion of the machine;

Fig. 7 is a further enlarged sectional view of the operating instrumentalities of the machine in operative position;

Fig. 8 is a perspective view of mechanism for adjusting a combined work gage and ejector with which the machine is provided;

Fig. 9 is a sectional view through the adjusting hand wheel of the mechanism shown in Fig. 8;

Fig. 10 is a front elevation of the machine as viewed in a direction parallel to the plane of the work with the mechanism at the rear of the machine omitted;

Fig. 11 is an enlarged view similar to Fig. 10 of the operating instrumentalities of the machine in operative position, the work support and clamping member being shown in section;

Fig. 12 is a plan view of a quarter lining after the machine has operated thereon; and

Fig. 13 is a perspective view, partly broken away, of the heel portion of the quarter lining in the position it assumes when bent around the rear end of a last.

The machine comprises a lower frame 16 adapted to be mounted on a bench or other support and having hinged to its upper portion on pivot pins 18 (Fig. 1) a cover 20 which may be swung back about the pins 18 to expose power driven mechanism of the machine mounted in the frame 16. Journaled in bearings 22 (Fig. 3) located at opposite sides of the frame 16 is a cam shaft 24 (Figs. 1 and 3) which carries a plurality of cams for actuating the operating instrumentalities of the machine. The power drive of the machine is provided by a constantly rotating pulley 26 arranged to rotate in a clockwise direction, as viewed in Fig. 1, and mounted on one end of a fixed shaft 28 supported in bearings 30, 32 projecting forwardly from the rear wall of the frame 16, the shaft being secured against rotation by a pin 34 in the bearing 30. The bearings 30, 32 are provided with upwardly extending portions having horizontal surfaces to which is secured, by screws 36, an oil container or trough 38 which supplies oil for lubricating various moving parts of the machine by a somewhat intricate oiling system including a plurality of tubes 40 containing wicks which feed the oil to different parts of the machine. Since this oiling system forms no part of the present invention it will not be described in detail herein.

The pulley 26 may be motor driven or it may be driven by factory power, as desired. The pulley is secured by screws 42 to a sleeve 44 (Fig. 3) loosely mounted on the fixed shaft 28 and carrying near its inner end, as viewed in Fig. 3, a small pinion gear 46, the sleeve being held on the shaft by a retaining plate 48 secured to the shaft by a screw 50. The pinion 46 meshes with a large gear 52 mounted on the cam shaft 24, the gear 52 being associated with the clutch mechanism for driving the cam shaft.

As herein illustrated, the clutch mechanism is of the general type disclosed in Letters Patent of the United States No. 1,351,138, granted August 31, 1920, on an application filed in the name of R. B. Smith. The gear 52 has an outwardly tapering hub portion 54 of substantial size and is bored internally at 56 to receive a bushing 58 which is fast in the hub and rotates constantly with the gear about a sleeve 60 secured to the cam shaft 24 by a pin 61. Mounted for sliding movement axially of the shaft on a re-

duced portion of the sleeve 60 is a semi-circular clutch member or dog 62 having a wedge-shaped tail portion 64 (Fig. 3). The clutch dog 62 carries a pin 66 which has a sliding fit in an opening in the sleeve 60 so that the clutch dog will rotate with the sleeve, the pin 66 being arranged to enter holes formed in an annulus or collar 68 secured by pins 70 at the bottom of the bore 56 of the gear 52. The pin 66 and member 62 are normally urged toward the gear by a compression spring 72 seated in an opening in the sleeve 60 and pressing against a small pin 74 mounted transversely in the sliding pin 66. The pin 66 is normally held out of engagement with the collar 68, so that the gear 52 rotates idly on the sleeve 60, by one end of a clutch pin 76 slidably mounted in a bracket 78 secured to a support 79 (Fig. 1) formed in the frame 16. The pin 76 is connected at its other end to a chain 80 running over a pulley 82 mounted on a fixed shaft 34 secured by set screws 83 in bearings 85 projecting forwardly from the frame 16, the chain 80 connecting with a treadle (not shown) on the machine. The clutch pin 76 is urged rearwardly of the machine to hold the clutch dog 62 away from the sleeve 60 by a spring 86 (Fig. 1) mounted between the legs of a bifurcated portion of the pin and bearing 88 at its forward end against a confining strap 88 screwed to the bracket 78.

When the operator depresses the treadle the pin 76 is pulled away from the clutch dog 62, thus permitting the pin 66 to engage in one of the holes in the collar 68 which is rotating with the gear 52. This connects the sleeve 60 to the rotating gear and, since the sleeve 60 is pinned to the cam shaft 24, rotates that shaft. The operator may then release the treadle so that the clutch pin 76 will return to its initial position and engage the wedge shaped portion of the dog 62 after one revolution, thereby withdrawing the sliding pin 66 from its connection with the gear 52 and stopping the rotation of the cam shaft.

In order to cause the cam shaft 24 to stop quickly and in substantially the same position at the end of each revolution, the machine is provided with a brake member consisting of a strap or band 90 (Fig. 1) of suitable brake material encircling the lower half of a spool shaped portion formed on the hub of one of the cams of the machine. The brake 90 is normally pulled against the spool by rods 92 secured to the opposite ends of the brake and extending upwardly through a projection or ledge 93 formed on one of the arms which carries part of the operating instrumentalities of the machine. The rods 92 extend upwardly beyond the projection 93 and have compression springs 94 surrounding their upper portions, the springs 94 being held in position by nuts 96 whereby the pressure of the springs may be varied. It will be seen from the foregoing that the brake is automatically released as the cam member upon which it operates lowers the lever or arm supporting the rods 92 and, conversely, the brake is applied as the cam elevates this arm. As herein illustrated, the brake is associated with the hold-down or clamping cam and with the arm which carries the work clamping mechanism of the machine because this arm is actuated with respect to the other mechanisms of the machine to release and apply the brake at the proper time.

Referring now to the mechanism at the front of the machine, the frame 16 has two forwardly projecting walls 98 connected by a cross portion 100 (Fig. 10) and having formed in the outer

sides of their upper portions forwardly and downwardly extending grooves or shoulders 102 inclined at an angle of approximately 15° to the horizontal and in which are secured by screws 104 a pair of vertical guide plates 106, preferably chromium plated. Each plate is provided with an elongated slot 108 parallel to the shoulder 102 and approximately $\frac{3}{8}$ of an inch high. These slots form guideways for assisting in the introduction of a quarter lining into the machine in a position to be operated upon and they are of sufficient length rearwardly of the machine to extend some distance beyond the means for supporting the quarter lining.

15 The mechanism for supporting quarter linings in operative position in the machine comprises a substantially rectangular or oblong block 110 resting on inwardly projecting shelves or shoulders 112 formed on the upper ends of the walls 198, the supporting block 110 also being located at an angle of approximately 15° to the horizontal to facilitate the introduction and removal of the work in the machine and being retained in position by screws 114 which fasten the block to the guide plates 106. The supporting block 110 is provided with a substantially central opening or hole 116 (Figs. 1, 4, 6 and 11) which is generally triangular in shape but with the corners of the triangle substantially rounded to form an 30 irregular ellipse. The base of the triangle is considerably greater than its altitude and this base or, to state it another way, the major axis of the ellipse extends widthwise of the supporting block, as viewed in Fig. 11, or in the direction of the 35 greatest dimension of a quarter lining mounted on the block. The forward side of the upper surface of the block 110 is provided with small teeth or corrugations 118 (Figs. 6 and 7) which tend to grip the work and hold the clamped portion thereof against movement during the operation thereon, as will be hereinafter explained.

In placing a quarter lining in position to be operated upon the operator grips the opposite ends of a quarter lining such, for example, as that indicated by 120 in Fig. 12, and introduces it preferably grain side up into the inclined slots 108 in the guide plates 106. He then moves it rearwardly in the slots until the intermediate or central portion of the lining overlies or spans the opening 116 in the supporting block 110. Since the block 110 is located at an angle of about 15° to the horizontal to facilitate the introduction and ejection of the work in the machine, it is desirable for the operator to hold the work in position until it has been gripped by the clamping mechanism and, accordingly, the guide plates 106 at this time act as guards to prevent injury to the operator's hands during the work clamping operation.

60 The machine may be provided with supporting blocks 110 of different sizes, that is, blocks having openings therein which are of proper sizes to accommodate large quarter linings for use in men's shoes and blocks to accommodate quarter linings for use in smaller shoes such as women's and children's shoes. To change the supporting block it is necessary only to remove the opposite screws 114 and slide the block out of the machine and introduce another block. When the quarter lining is properly positioned on the supporting block 110 a substantial width of the marginal portion of the quarter lining is contacting with the block entirely around the opening 116.

In order to locate the quarter lining in the proper position forwardly and rearwardly of the

5 machine the latter is provided with adjustable gages located at opposite sides of the supporting block 110 as viewed in Fig. 10. These gages comprise rectangular bars 122 (Figs. 6, 7 and 11) several inches long and having elongated slots 124 formed in their forward portions, these slots corresponding in height to the slots 108 in the guide plates 106 and being located in the same plane. The gage members 122 are mounted for sliding movement relatively to the supporting block 110 forwardly and rearwardly of the machine in guideways 126 formed by slots in the side plates 106 (Fig. 11) which register with shoulders or slots formed in adjacent portions of the supporting block, these guideways 126 being 10 also located at an angle of substantially 15° to the horizontal, as shown in Figs. 1 and 6.

15 The gage members 122 are adjustable in the guideways 126 relatively to the supporting block 110 and are also arranged for sliding movement 20 in the guideways to eject the work from the machine after it has been operated upon. The mechanism for adjusting the gages and for actuating them to eject the work will now be described. Each gage and ejector member 122 has 25 pivoted to its inner end by a pin 128 a rearwardly extending rod 130 the rear portion of which is threaded into a tubular extension member 132 which, in turn, is pivotally connected by a stud screw 134 to the upper end of an arm 136 30 secured to a shaft 138 by a pin 140 (Figs. 3 and 8); the arms 136 for both gages being interconnected by a cross portion 141 extending transversely of the machine below the shaft 138. Loosely mounted on the shaft 138, adjacent to 35 the left-hand arm 136, as viewed from the front of the machine, is a bell crank lever 142 (Fig. 8) having a lower rearwardly extending arm 144 carrying a roll 146 which engages a cam 148 (Figs. 1 and 3) secured to the cam shaft 24 by 40 a pin 150. The roll 146 is normally held against the high part of the ejector cam by a tension spring 152 secured at its lower end to the arm 144 and being hooked at its upper end over a projection 154 formed on the oil trough 38. By 45 this arrangement the roll 146 is caused to ride onto the low part of the cam 148 through the action of the spring 152 so that the work ejecting motion of the ejectors, although predetermined by the shape of the cam, is nevertheless 50 yielding because of the tension spring 152. This insures against injury to either the work or the machine in case the work should happen to catch or stick during the ejecting operation.

55 The shaft 138 is loose in bearings 156 (Fig. 3) 55 formed at opposite sides of the machine and, accordingly, will turn or oscillate with the interconnected arms 136 under the action of the cam 148. The bell crank lever 142 is provided at its upper end with a laterally extending boss 158, 60 best shown in Fig. 8, in which is rotatably mounted a pin 160 having a disk 162 formed on the end thereof nearest the arm 136. The disk 162 carries an eccentric pin 164 which extends into a block 166 mounted for sliding movement 65 in a slot 168 formed lengthwise of the arm 136. The pin 160 extends beyond the boss 158 and carries a hand wheel 170 provided on its inner side with a series of holes 172. The boss 158 has an upwardly extending projection 174 formed 70 thereon in which is fixed a small indexing pin 176 (Figs. 8 and 9) having an end projecting in position to enter the holes 172. The hand wheel 170 is mounted for movement lengthwise of the pin 160 by a key 178 fixed in the shaft by a pro- 75

jection 180 and engaging a keyway 182 in the hand wheel. The hand wheel is urged against the boss 158 by a compression spring 184 held on the pin 160 by a washer 186 and pin 188.

- 5 When it is desired to adjust the initial position of the combined gages and ejectors 122 forwardly or rearwardly of the machine relatively to the supporting plate 110, the operator grasps the hand wheel 170 and pulls it away from the indexing pin 176 against the spring 184 and turns the hand wheel and pin 160 to cause the eccentric pin 164 to move the block 166 in the slot 168 and thereby to change the angular position of the arms 136 relatively to the arm 142 which, in turn, will slide the gages and ejectors forwardly or rearwardly in their slots 126 into the desired position relatively to the supporting block 110. The hand wheel 170 is provided with numerals opposite the indexing holes to indicate 10 the position of the handle for operating on the various sizes of quarter linings. The throw of the ejector cam 148 is sufficient to eject the work piece from the machine when the members 122 are acting as ejectors irrespective of the forward 15 or rearward position into which they have been adjusted for operating as gages.

In order that the operator need not be concerned with the ejection of the work pieces from the machine and may devote his attention entirely to the introduction of the work, the machine is provided with a work receiving receptacle or tray 190 (Figs. 1 and 2) pivoted on the side plates 106 by pins 192 and having a rectangular portion 194 for receiving the work as it is ejected from the machine and also a forward V-shaped portion 196 on which work pieces to be operated on may be stacked, thus providing a convenient arrangement for relieving the operator from unnecessary work and for speeding up the production of the machine.

40 After the quarter lining has been positioned properly on the work supporting block 110, it is clamped by power operated mechanism so that the portion of the quarter lining at the periphery of the opening 116 in the supporting block and a substantial width of the material surrounding the opening will be under relatively heavy pressure in order that the clamped portion will remain flat and will not be deformed or distorted during the stretching and conforming operations which are to be performed on the portion of the quarter lining which is spanning the opening. The work clamping mechanism comprises a substantially U-shaped lever or arm 200 pivoted on the fixed shaft 28 and located centrally with respect to the supporting block 110. Near its forward end the arm 200 is provided with downwardly extending ears 201 (Figs. 1 and 6) between which is pivoted on a pin 202 a link 204 the lower end of which is pivotally connected by a pin 206 to a cam lever 208, the forward end of the cam lever being pivotally mounted on the fixed shaft 84. As illustrated in Fig. 1, the cam lever 208 is directly behind another cam lever of substantially the same shape and, accordingly, only a portion of the lever 208 appears through a break in the second lever referred to.

Near its rear or inner end the cam lever 208 70 carries a roll 210 (Figs. 1 and 3) which rides on the periphery of a cam 212 hereinafter referred to as the holdown or clamping cam, the roll 210 being directly behind a similar roll associated with the second cam lever mentioned above and, accordingly, not showing separately in Fig. 1.

The cam 212 is secured to the cam shaft 24 by a pin 214 (Fig. 3) so that the cam moves only with the shaft. When the cam 212 is rotated one revolution by the power mechanism already described, the cam roll 210, which is maintained in engagement with the cam 212 by a tension spring 216 hooked at its lower end to the cam lever 208 and at its upper end to the trough 38, swings the lever 208 downwardly about its pivot 84 and, through the link 204, swings the clamping or holdown arm 200 a predetermined distance downwardly about its pivot 28 to move the clamping arm into clamping relation with the work. It will be seen from the foregoing that the operative movement or stroke of the arm 200 is positive and predetermined by the shape of the cam 212.

The forward portion of the arm 200 is bifurcated to form two arms 218 each provided with two bosses 220 located at right angles to the length of the arm, the bosses together forming the four corners of a rectangle similar to, but somewhat smaller in dimensions than, the supporting block 110. The bosses 220 are hollow and contain relatively heavy compression springs 222 (Figs. 1, 6 and 10) surrounding screws 224 which extend through the upper ends of the bosses and support on their lower ends a clamping plate 226, the plate having countersunk holes therein for receiving the heads of the screws. Lock nuts 228 on the upper ends of the screws hold the clamping plate 226 against the pressure of the compression springs 222. The clamping plate 226 is provided with an opening 230 (Figs. 4 and 7) corresponding substantially in shape or outline to the opening 116 in the supporting block 110 but being slightly smaller than that opening for operating on small shoes, so that the work piece will be clamped completely around the periphery of the elliptical or generally triangular opening in the supporting block. The shape of the opening in the clamping plate 226 is best shown in Fig. 4.

The plate 226 has extending downwardly from its lower side an irregularly hexagonal portion 45 considerably larger than the opening 230 in the plate and through which the opening extends, this hexagonal portion having horizontal grooves 232 (Figs. 4 and 5) formed in its inner side faces and also across the opposite corners at its forward side, as shown in Fig. 4. Below the grooves 232 are ribs 234, as best shown in Fig. 5, and this construction forms the means for securing to the lower surface of the clamping plate a covering of relatively soft resilient material 236 such, for example, as rubber of substantial thickness for engaging the work piece which is to be clamped against the support, the rubber facing member 236 having a groove and a rib 238 for engaging the groove 232 in the clamping plate and thereby holding the facing member securely in position. The rubber facing 236 is also provided at its forward edge with a vertical V-shaped rib 233 which serves as an indicator or gage to assist in positioning the work widthwise of the supporting block.

In order to remove a substantial part of the load from the holdown or clamping cam 212 and yet apply the desired pressure to the work, the four compression springs 222 are initially compressed a predetermined amount when the mechanism is assembled so that a relatively small movement of the clamping plate 226 against the compressed springs will produce the required pressure. Preferably, each spring 222 is com- 70 75

pressed initially to exert a pressure of approximately two hundred and fifty pounds so that as the resilient facing member 236 engages the work piece through the operation of the holddown cam 5 and is pressed thereagainst sufficiently to take the pressure away from the lock nuts 228, a pressure of approximately one thousand pounds will be transferred from the plate 226 to the work piece. In this way there is no substantial load 10 on the cam during the first part of its rotation. Moreover, since the initial compression of the springs obviates the necessity of their being compressed during the operation of the machine by the action of the clamping cam 212, the throw 15 or rise of the cam need only be sufficient to locate the clamping plate when inoperative a proper distance from the supporting block 110 to permit the ready introduction of the work. In other words, the throw of the cam 212 may be 20 considerably less than would be required if the springs were not under initial compression and still leave sufficient space between the clamp and the supporting block to introduce the work. Since the holddown cam will be under the load 25 of the clamping pressure only while the work is actually engaged by the clamp, and since the work is clamped and released during a relatively small portion of the cycle of the machine, the speed of the machine may be considerably greater than 30 it could otherwise be.

It will be seen that the particular mounting of the clamping plate herein disclosed also operates to distribute or equalize the pressure applied to various portions of the work piece so 35 that if the work piece is not of uniform thickness throughout, the clamping plate can adjust itself into such a plane that the rubber facing 236 will engage all portions of the work piece with substantially the same amount of pressure. 40 As shown in Fig. 7, the rubber facing 236 has a hole 240 in its central portion which registers with the opening 230 in the clamping plate 226.

As stated, the quarter lining is preferably introduced into the machine grain side up and with 45 the lower or lasting margin of the lining nearer the operator, this margin, as shown in Fig. 12, being relatively narrow across the full width of the quarter lining. In order that this narrow lasting portion of the quarter lining will not slip 50 inwardly toward the opening 116 during the molding operation and thereby cause the periphery of the lining to lose its original shape, the front portion of the rubber facing 236 which engages the quarter lining is backed up or supported by a rib 55 242 (Fig. 7) projecting downwardly from the clamping plate 226. The teeth 118 also assist in preventing this forward clamped portion of the quarter lining from slipping. Thus, the clamped portion of the work which surrounds the opening 60 116 in the supporting plate will be prevented from slipping around the entire opening 116 and will be held perfectly flat during the conforming or molding operation. Moreover, the pressure of the clamping member is such that this clamped portion of the quarter lining surrounding the opening 65 116 is not stretched or distorted in any way, thereby preserving the original shape or peripheral dimension of the quarter lining.

The mechanism for forming or molding a bulge 70 in the central portion of the quarter lining comprises an arm 244 pivoted at its inner end on the shaft 28 and extending forwardly substantially midway between the opposite side portions of the yoked arm or lever 208. At its forward end the 75 arm 244 is provided with a rectangular boss 246,

open at the front and top and having a cover plate 248 secured thereto by screws 250. The boss 246 has a rectangular opening therein in which is secured, by the cover 248, the rectangular shank portion 252 of a molding member or plunger 254. The work engaging portion of the plunger 254 is preferably chromium plated to reduce friction against the work piece and is shaped in plan view (Fig. 4) to conform substantially to the peripheries of the openings in the clamping plate 226 10 and supporting block 110 except that it is a little smaller than the opening 230 in the clamping plate so that it will pass readily therethrough and into engagement with the portion of the work piece that is spanning the opening 116 in the supporting block. That is to say, the plunger is elongated in the direction of the longest dimension of a quarter lining on the supporting block 110 and is generally triangular in plan view with the corners of the triangle substantially 15 rounded to produce an irregular ellipse. The plunger 254 is rounded or convex on its lower or work engaging surface and tapers gradually toward its opposite ends, as viewed in Figs. 10 and 11, so that its central portion lies nearer the initial plane of the work than its opposite end portions. The bulge formed by the plunger in the quarter lining will accordingly fit the curved or convex portion of the heel end and side portions of a last without any appreciable wrinkling or 20 distortion of the quarter lining which, as shown in Fig. 12, is preferably formed of a single piece of material such as leather. In other words, the shape of the work engaging surface of the plunger or molding member 254 is such that it will mold 25 and stretch a substantial area of the exposed portion of the one piece quarter lining in a manner to cause the molded portion to fit the convexity or curvature at the heel end and side portions of a last. Moreover, as indicated above, the 30 smooth polished surface on the plunger reduces friction between it and the work piece to such an extent that the work piece will stretch substantially equally throughout the entire area spanning the opening in the supporting member and thereby stretch the fibers at this portion of the material beyond their limit of elastic recovery so that there will be little tendency thereafter for the leather to contract and offset the results of the 35 molding operation.

The arm 244 is swung about its pivot to move the plunger 254 into and out of operative position by a link 256 pivotally secured at its upper end between ears 258 on the lower side of the arm by a pin 260 and connected at its lower end by a 40 pin 262 to a cam lever 264, referred to above as being directly in front of the cam lever 208 and pivoted on the fixed shaft 84. The cam lever 264 extends rearwardly and carries a roll 266 (Figs. 1 and 3) which rides on the periphery of a cam 45 268 which may be called the plunger cam, the roll being held against the cam by a spring 270 extending between the cam lever 264 and a projection on the oil trough 38. When the plunger cam 268 is rotated the lever 264 is swung downwardly about the pivot 84 and, through the link 256, the arm 244 is moved downwardly a predetermined distance to operate the plunger and conform or mold the work piece, the annular portion of which is then clamped in a substantially 50 flat position on the supporting block 110.

Since the operative movement of the plunger 254 is positive and fixed by the shape of the cam 268, it is desirable to be able to vary the initial position of the plunger with respect to the work 55

so that it may operate satisfactorily on different grades and sizes of quarter linings. To this end the rectangular shank portion 252 of the plunger is arranged for heightwise adjustment in the 5 boss 246 by means of a screw 272 (Fig. 6) threaded into a tapped hole in the shank 252 and provided at its upper end with a hand wheel 274 whereby the screw may be turned to move the plunger heightwise relatively to the end of the arm 10 244. This adjustment is limited by a small pin 276 mounted in the cover plate 248 and entering a vertical slot 278 in the shank portion of the plunger. The screw 272 is prevented from turning of its own accord in the plunger by a spring 15 pressed detent 280 (Fig. 10) mounted in the upper portion of the boss 246 and arranged to enter a depression formed in the upper portion of the screw 272. The front side of the cover plate 248 is provided with a square opening and the forward 20 surface of the rectangular shank 252 of the plunger is graduated (Fig. 10) so that the adjustment may be made in accordance with the size of the work piece being operated upon.

It will be seen that, as the plunger descends into 25 engagement with the quarter lining and forces the portion thereof spanning the opening 116 downwardly in the supporting block and then returns to its inoperative position, there will be a tendency for the molded portion of the quarter lining to 30 remain in the opening rather than to return to its original flat position. This would, of course, interfere with the operation of the ejectors 122 which operate thereafter to eject the work from the machine. Accordingly, means is provided to 35 insure that the work piece will not remain depressed too far into the opening 116 when the ejectors operate. This means comprises a stripper member consisting of a small shaft 282 mounted for heightwise sliding movement in a boss 284 40 formed on the cross portion 100 of the frame 16 which extends between the side walls 98. The upper end of the shaft 282 has an enlarged plate-like portion 286 located directly under the plunger and adapted to engage the work piece 120, as 45 shown in Figs. 7 and 11, when the plunger is operating thereon and to move downwardly yieldingly under the action of the plunger. The stripper member is normally maintained at the upper limit of its heightwise movement and is permitted 50 to yield under the force of the plunger by a compression spring 288, the upper limit of said heightwise movement being determined by nuts 290 threaded on the lower end of the shaft 282. Accordingly, when the plunger 254 is returning to 55 its inoperative position after molding the quarter lining, the stripper 282 moves upwardly under the plunger and work piece and returns the molded portion of the work piece to a more nearly flat position so that it does not extend sufficiently into 60 the opening 116 to interfere with the ejection of the quarter lining from the machine by the ejectors 122.

In the operation of the machine, the operator 65 selects a quarter lining from the tray 190 and, holding the opposite end portions of the quarter lining, introduces it, preferably grain side up, into the slots 108 in the guide plates 106. He moves the work piece rearwardly at the same time centralizing it widthwise of the machine by the aid 70 of the projection 233 on the rubber facing 236 so that the central portion of the quarter lining will overlie or bridge the opening 116 in the supporting plate 110. The rearward position of the quarter lining is determined by the position of the 75 ends of the slots 124 in the gages 122, which may

be adjusted beforehand in accordance with the size of the work piece by the hand wheel 170.

The operator then depresses the treadle of the machine to engage the clutch and rotate the cam shaft 24. The clamping arm 200 thereupon descends to bring the rubber facing 236 of the clamping plate 226 into clamping engagement with the work under the pressure of approximately one thousand pounds. As stated, the shape and construction of the clamping member 10 is such that the quarter lining will be clamped firmly entirely around the periphery of the opening 116 in the supporting block and a substantial portion of the quarter lining surrounding this opening will also be clamped in a flat position, 15 thereby insuring that the quarter lining will not slip to distort the outline thereof or to permit a greater area to be molded than is desired. While the clamping plate is moving into operative position the plunger 254 is descending and, after the 20 work is securely clamped, moves against the center of the portion of the quarter lining spanning or bridging the opening 116 and descends a predetermined distance into said opening to mold and stretch the material spanning the opening 25 the desired amount. As stated above, the smooth polished surface of the plunger permits the entire unsupported portion of the quarter lining overlying the opening 116 to stretch substantially uniformly throughout, and the plunger will have been 30 adjusted to the proper heightwise position relatively to its operating arm to insure that the stretching action will be just sufficient to produce the molding effect desired without tearing the leather. 35

The plunger returns almost immediately to inoperative position and, while it is so returning, the clamp or holdown member 226 is released from the work by the action of its cam and the ejectors 122 are then operated to eject the conformed 40 work piece from the machine. The ejecting operation is facilitated by the action of the stripper member 282 which moves the molded portion of the quarter lining out of the opening 116 so that the quarter lining will slide readily off the supporting block 110. 45

Figs. 12 and 13 illustrate the quarter lining after a bulge 292 has been formed therein, Fig. 12 showing the outline of the bulge, as seen in plan view, and Fig. 13 showing the bulge as it would 50 appear with the quarter lining bent into a position for engaging the curvature at the heel and side portions of a last. It will be seen from these figures that the molded portion of the quarter lining is located substantially at its central or intramarginal area and covers a relatively large elliptical shaped portion which tapers gradually toward the opposite ends of the quarter lining. It has been found that this particular shape and size of bulge is best adapted to produce a proper fit of a one-piece quarter lining over the curvature at the heel end of a last. Since the molded area has been stretched as well as conformed by the shaping operation thereon, it will retain this shape or bulge permanently so that a quarter lining which 60 has just been molded need not be used immediately in a shoe. 65

Having thus described my invention, what I claim as new and desire to secure by Letters Patent of the United States is:

1. A machine for operating on quarter linings for shoes having, in combination, means for supporting a quarter lining with a portion thereof spanning an opening, means for clamping the quarter lining entirely around the periphery of 70 75

5 said opening, and chromium plated means for stretching that portion only of the quarter lining which spans the opening substantially uniformly throughout its entire area, said means being constructed and arranged to engage only a part of the portion of the quarter lining spanning the opening.

10 2. A machine for operating on quarter linings for shoes having, in combination, means for supporting a quarter lining in a substantially flat position with an intramarginal portion thereof bridging an opening, yielding means for clamping the quarter lining around the entire periphery of said opening, and means for molding only the 15 portion of the quarter lining bridging said opening to form a bulge therein, said means being adapted also to stretch the entire bridging portion of the quarter lining substantially uniformly throughout its entire area while engaging only the central 20 part of said bridging portion.

25 3. A machine for operating on quarter linings for shoes having, in combination, means for supporting a quarter lining with a generally triangular intramarginal portion thereof unsupported, means for clamping the quarter lining around the periphery of the unsupported portion, a plunger for molding said unsupported portion to form a generally triangular last-receiving bulge, said plunger having a highly polished work engaging surface adapted to slip readily on the work without substantial friction and thereby to permit the entire unsupported portion to stretch substantially uniformly during the molding operation, and means for actuating said plunger so 30 that only a part of its work engaging surface engages said unsupported portion during its operative movement, thereby further facilitating the uniform stretching action.

35 4. A machine for operating on quarter linings for shoes having, in combination, means for supporting a quarter lining with its intramarginal portion spanning a substantially elliptical opening in the supporting means, the longer axis of said opening extending lengthwise of the quarter 40 lining means for clamping a substantial width of said quarter lining completely around the periphery of said opening, and a plunger movable into said opening for molding the portion of the quarter lining spanning the opening, said 45 plunger being formed and operated to engage only an intramarginal area of said portion progressively from center to edge, thereby stretching the part of said portion which is bridged between the plunger and the periphery of the opening, after the plunger engages the quarter lining, the work engaging surface of said plunger being 50 polished to reduce friction and thereby to permit the portion of the quarter lining contacting therewith to slip readily thereon and thus to stretch as much as the part bridged between the plunger and the periphery of the opening.

55 5. A machine for operating on quarter linings for shoes having, in combination, a supporting member having an opening therein, means for clamping a quarter lining on said member with a central portion thereof bridging said opening, a plunger operable to engage only the central part of the portion of the quarter lining located within the periphery of said opening and for shaping said 60 part to form a bulge and for simultaneously stretching the portion of the quarter lining located within the periphery of said opening but not engaged by said plunger, said plunger being arranged to move a predetermined distance and 65 having a chromium plated work engaging portion

70 arranged to permit the central part of the quarter lining engaged thereby to slip readily thereon and thereby to stretch substantially the same amount as the portion located within the periphery of said opening but not engaged by the plunger during 75 its operative movement.

7. A machine for operating on quarter linings for shoes having, in combination, power operated means for clamping a quarter lining yieldingly completely around its marginal portion with the 10 entire portion thereof within the periphery of the clamped portion unsupported, a plunger for operating on the unsupported portion of said quarter lining, and means for relatively moving the quarter lining and the plunger a predetermined 15 distance to shape the entire area of said unsupported portion by contact of the plunger with only an intramarginal area of said unsupported portion.

20 7. A machine for operating on quarter linings for shoes having, in combination, power operated means for clamping an annular portion of a quarter lining, a plunger for operating on said quarter lining, power operated means for actuating said plunger, and means for adjusting the 25 plunger relatively to its actuating means thereby predetermining the effective stroke of said plunger.

20 8. A machine for operating on quarter linings for shoes having, in combination, power operated 30 means for clamping a quarter lining with a central portion thereof spanning an opening, a plunger for molding said central portion, power operated means for relatively moving the plunger and the clamping means to cause the plunger to shape the 35 central portion of the quarter lining, and means operating on the plunger alone for varying the operative effect of said relative movement.

35 9. A machine for operating on quarter linings for shoes having, in combination, means for 40 clamping a quarter lining with a central portion thereof unsupported, a plunger movable to engage the unsupported central portion of the quarter lining and to shape said portion to form a last receiving bulge, power operated means for 45 moving the plunger a predetermined distance in performing the shaping operation, and means for adjusting the position of the plunger relatively to said power operated means.

45 10. A machine for operating on quarter linings 50 for shoes having, in combination, means for supporting a quarter lining to be operated upon, single means for clamping an annular portion of the quarter lining against the supporting means, power operated means for actuating said clamping means, said power operated means being constructed and arranged to move the clamping means a predetermined distance during the clamping operation, means for causing the single clamping means to apply pressure uniformly to 55 all parts of the clamped annular portion, and a plunger movable independently of said clamping means for operating upon the quarter lining.

60 11. A machine for operating on quarter linings for shoes having, in combination, a support for 65 holding a quarter lining in a position to be operated upon, single means for clamping an annular portion of the quarter lining against the support, springs carried by said clamping means and compressed initially under a predetermined pressure, 70 and a cam for moving the clamping means, said cam having an operative portion thereon sufficient only to transfer the pressure of said springs from the clamping means to the work, said construction minimizing the distance the clamping means 75

has to travel to apply predetermined pressure to the work.

12. A machine for operating on quarter linings for shoes having, in combination, a support for holding a quarter lining in a position to be operated upon, means for clamping the quarter lining against the support, a cam for moving the clamping means a predetermined distance into clamping relation with the work, and springs carried by said clamping means and initially exerting a predetermined pressure against the work engaging portion thereof which pressure is transferred to the work through the movement of the clamping means by the cam, the pressure confined in said springs relieving the cam from any pressure applying load until the last part of its operative movement.

13. A machine for operating on quarter linings having, in combination, means for supporting a quarter lining to be operated upon, means movable toward said supporting means for clamping the quarter lining in operative position, means for initially confining a predetermined pressure within the clamping means itself, means for moving the clamping means only a sufficient distance toward the work to cause the pressure initially confined in said clamping means to be exerted on the work, and means independent of movement of the clamping means for operating on the quarter lining.

14. A machine for operating on quarter linings having, in combination, means for supporting a quarter lining to be operated upon, a clamp for pressing the quarter lining against the supporting means, an arm carrying said clamp, springs under predetermined compression between the clamp and the arm urging the clamp away from said arm, and a cam for moving the arm toward the supporting means to transfer the pressure of the compressed springs to the work, said cam having a predetermined short throw and operating without any pressure applying load during the greater part of its operative movement.

15. In a machine for operating on quarter linings for shoes, a block for supporting a quarter lining to be operated upon, an arm movable relatively to said block, a plate carried by the arm for clamping the work on the block, springs urging the plate away from the arm under substantial initial pressure, bolts passing through the plate and arm and surrounded by said springs, nuts on said bolts for retaining them and the plate on the arm against the pressure of said springs, and a cam for moving the arm only a sufficient distance to transfer the initial pressure of said springs from the plate to the work.

16. In a machine for operating on quarter linings for shoes, means for clamping a work piece in position to be operated upon, said means comprising a fixed support, an arm movable relatively to the support, a cam for actuating said arm, a substantially rectangular work engaging plate carried by the arm for pressing the work piece against the support and thereby clamping said work piece, and springs between the arm and the four corners of the plate for automatically equalizing the pressure applied by the clamping means to the work piece.

17. A machine for operating on quarter linings for shoes having, in combination, means for clamping an annular portion of a quarter lining with an intramarginal portion thereof unsupported, and means for stretching said unsupported portion to form a last receiving bulge, said stretching means comprising a plunger having a convex work engaging portion elongated in the direction of the longest dimension of the quarter lining and tapering into rounded end portions from a relatively wide central portion.

18. A machine for operating on quarter linings for shoes having, in combination, means for clamping an annular portion of a quarter lining with an intramarginal portion thereof unsupported, and means for molding said unsupported portion to form a last receiving bulge, said molding means comprising a plunger having a convex work engaging surface relatively wide at the center and tapering gradually into rounded end portions, the longest dimension of the plunger extending in the direction of the longest dimension of the quarter lining.

19. A machine for operating on quarter linings for shoes having, in combination, means for clamping an annular portion of a quarter lining with an intramarginal portion thereof unsupported, and means for stretching said unsupported portion to form a last receiving bulge, said stretching means comprising a plunger having a generally triangular shape in plan view, the base of the triangle extending in the direction of the longest dimension of the quarter lining, the work engaging portion of said plunger being transversely convex.

20. A machine for operating on quarter linings for shoes having, in combination, means for clamping an annular portion of a quarter lining with an intramarginal portion thereof unsupported, and means for stretching said unsupported portion to form a last receiving bulge, said stretching means comprising a plunger being approximately triangular in plan view with the base of the triangle greater than its altitude and said base extending in the direction of the greatest dimension of the quarter lining.

21. A machine for operating on quarter linings for shoes having, in combination, means for clamping an annular portion of a quarter lining with an intramarginal portion thereof unsupported, and means for molding and stretching said unsupported portion to form a last receiving bulge, said molding and stretching means comprising a plunger approximately elliptical in plan view with its major axis extending in the direction of the greatest dimension of the quarter lining.

22. A machine for operating on quarter linings for shoes having, in combination, means for clamping an annular portion of a quarter lining with an intramarginal portion thereof unsupported, and means for stretching said unsupported portion to form a last receiving bulge, said stretching means comprising a plunger having the shape in plan view of an irregular ellipse formed by rounding the corners of an obtuse isosceles triangle, the major axis of the irregular ellipse extending in the direction of the greatest dimension of the quarter lining.

23. A machine for operating on quarter linings for shoes having, in combination, means for supporting a quarter lining, said means comprising a substantially oblong member having an opening therein which is generally triangular in shape but with the corners of the triangle substantially rounded, the base of said triangle being greater than its altitude and extending lengthwise of said supporting member, and a plunger for shaping a portion of the quarter lining spanning said opening, said plunger conforming substantially in plan view to the shape of said opening and having a smooth convex work engaging portion

which tapers gradually toward the opposite end portions of the plunger, the central portion of the plunger lying nearer the initial plane of the work than the opposite end portions.

5 24. A machine for operating on quarter linings for shoes having, in combination, a support for holding a quarter lining, means for clamping said quarter lining on the support, said support having a generally triangular opening therein arranged to underlie an intramarginal portion of the quarter lining and conforming substantially in shape to a predetermined outline of a convex portion of the heel end and side portions of a last, said clamping means having a substantially rectangular work engaging surface thereon adapted to clamp a substantial area of the quarter lining surrounding the opening in said support and having an opening therein arranged to register with the opening in the support, and 10 20 a plunger arranged to pass readily through said openings to shape the entire portion of the quarter lining spanning the openings.

25 25. A machine for operating on quarter linings for shoes having, in combination, means for supporting a quarter lining to be operated upon, and means for determining the position of the quarter lining relatively to the supporting means and for ejecting said quarter lining from said supporting means after it has been operated upon.

30 26. A machine for operating on quarter linings for shoes having, in combination, means for supporting a quarter lining to be operated upon, and power operated means acting on an edge portion of the quarter lining for ejecting it from the supporting means after it has been operated upon.

35 27. A machine for operating on quarter linings for shoe having, in combination, means for supporting a quarter lining to be operated upon, and power operated means for ejecting the quarter lining from the supporting means after the operation on the quarter lining has been completed, said means being arranged to act yieldingly on the quarter lining.

40 28. A machine for operating on quarter linings for shoes having, in combination, means for supporting a quarter lining to be operated upon, means for determining the position of the quarter lining on the supporting means, and means for adjusting said positioning means relatively to the supporting means, said adjusting means including an indexing member for adjusting the positioning means into a plurality of predetermined positions.

45 29. A machine for operating on quarter linings for shoes having, in combination, a support for holding a quarter lining to be operated upon, a gage for determining the proper position of the quarter lining on the support, means for varying the initial position of said gage relatively to the support for different types of work, and means for effecting relative movement of the gage and support to eject the quarter lining from the support after it has been operated upon.

50 30. A machine for operating on quarter linings for shoes having, in combination, a support for holding a quarter lining to be operated upon, a gage for determining the position of the quarter lining transversely of the support, means for moving the gage relatively to the support to eject the work therefrom after it has been operated upon, and means for varying the initial position of the gage relatively to the support without affecting the ejecting movement imparted to the gage by said moving means.

55 31. A machine for operating on quarter linings

for shoes having, in combination, a rectangular support for holding a quarter lining to be operated upon, members at opposite sides of said support and slideable relatively thereto for ejecting the quarter lining after it has been operated upon, power operated means for sliding said members relatively to the support, and means for varying the initial position of said members without altering the sliding movement imparted thereto by said power operated means.

10 32. A machine for operating on quarter linings for shoes having, in combination, a support for a quarter lining to be operated upon, gage members for determining the position of the quarter lining relatively to the support, means for varying the initial position of said gage members relatively to the support for work of different sizes, and means for moving said gage members transversely of the support to eject the work after it has been operated upon, said means being constructed and arranged to operate the gage members yieldingly so that the work will not be injured during the ejecting operation.

15 33. A machine for operating on quarter linings for shoes having, in combination, a support upon which a quarter lining may be placed by an operator to have work performed thereon, means for clamping the quarter lining under substantial pressure while held in position on the support by the operator, and means for preventing injury to the operator's hands during the clamping operation.

20 34. A machine for operating on quarter linings for shoes having, in combination, a support for a quarter lining to be operated upon, a gage for determining the position in which the work may be held by an operator on the support, means for clamping the work on the support, and means for preventing injury to the operator's hands during the clamping operation.

25 35. A machine for operating on quarter linings for shoes having, in combination, a support for a quarter lining to be operated upon, means for clamping the work on the support under substantial pressure, a gage for determining the position in which the work may be located by an operator on the support, means for actuating the clamping means after the work has been positioned on the support and while it is still held by the operator, and a guard for preventing injury to the operator's hands during the clamping operation.

30 36. A machine for operating on quarter linings for shoes having, in combination, means for supporting a quarter lining to be operated upon in a substantially flat position, means for clamping the quarter lining on said supporting means, a plunger for forming a last receiving bulge in an intermediate portion of the quarter lining, means for ejecting the quarter lining from the supporting means after the bulge has been formed therein, and means for preventing the bulged portion of the quarter lining from interfering with its ejection from the supporting means.

35 37. A machine for operating on quarter linings for shoes having, in combination, means for supporting a quarter lining in a flat position with an intramarginal portion thereof spanning an opening in the supporting means, means for forming a last receiving bulge in the portion of the quarter lining spanning said opening by displacing said portion into the opening, means for ejecting the quarter lining after the bulge has been formed, and means for automatically moving the bulged portion of the quarter lining out

of the opening prior to the ejecting operation, thereby preventing the bulge from interfering with the ejecting operation.

38. A machine for operating on quarter linings for shoes having, in combination, means for supporting a quarter lining with an annular portion overlying an opening in the supporting means, a power operated clamp movable relatively to the supporting means for clamping the work piece thereon, said clamp having an opening therein which registers with the opening in the supporting means, thereby exposing the work piece at said opening, a power operated plunger corresponding in shape to the openings in the clamp and supporting means for shaping the entire portion of the work piece overlying said openings to form a last receiving bulge, said plunger being adapted to stretch the material operated upon substantially equally throughout its entire area, power operated means for ejecting the work piece from the supporting means after the bulge has been formed therein, and resilient means operating automatically to prevent the bulge from interfering with the ejection of the work piece.

39. That improvement in methods of treating quarter linings for shoe which comprises clamping in a flat position against slippage a substantial marginal portion of a quarter lining completely enclosing an intramarginal portion substantially triangular in shape with the base of the triangle greater than its altitude and extending lengthwise of the quarter lining, the entire area of said intramarginal portion enclosed by said clamped portion being entirely unsupported, and forcing said unsupported portion out of said flat position

while still unsupported at any part thereof to form a last receiving bulge while simultaneously stretching the entire unsupported portion enclosed by said clamped portion a substantially uniform amount beyond the limit of its elastic recovery.

40. That improvement in methods of treating quarter linings for shoes which comprises clamping against slippage in its own plane a marginal portion of a quarter lining completely enclosing an entirely unsupported intramarginal portion of substantial area and approximately elliptical in shape with the major axis of the ellipse extending in the direction of the greatest dimension of the quarter lining, and forcing the entire unsupported elliptical portion of the quarter lining enclosed by the clamped portion out of its own plane while still unsupported at any part thereof by a plunger the surface of which has a small coefficient of friction with the unsupported elliptical portion, thereby producing a last receiving bulge in said unsupported elliptical portion and permanently stretching said portion substantially uniformly throughout its entire area.

41. A machine for shaping a heel lining preparatory to the lasting operation having, in combination, a work support having an aperture to be overlaid by the heel lining, a clamp for clamping the heel lining upon the work support, and means operating while the heel lining remains clamped upon the work support for producing a depression in that portion of the heel lining overlying the aperture.
